CLAIM

USPC **D19/166**

The ornamental design for a pen, as shown and described.

(58) **Field of Classification Search**

DESCRIPTION

USPC D14/411; D19/35, 36, 41–51, 53–58;
24/11 R, 11 F, 11 P; 401/52, 99–109,
401/192, 195, 196

FIG. 1 is a front perspective view of a pen showing my new design;

See application file for complete search history.

FIG. 2 is a front elevation view thereof;

FIG. 3 is a rear elevation view thereof;

FIG. 4 is a left side elevation view thereof, with the right side elevation view being a mirror image of the left side elevation view;

FIG. 5 is an enlarged top plan view thereof;

FIG. 6 is an enlarged bottom plan view thereof;

FIG. 7 is a lower front perspective view of the pen shown in FIG. 1, shown without the cap for the convenience of illustration;

FIG. 8 is a front elevation view thereof, with the rear, right side, and left side elevation views being a mirror image of the front elevation view;

FIG. 9 is an enlarged top plan view thereof; and,

FIG. 10 is an enlarged bottom plan view thereof.

The broken lines shown in FIGS. 5, 6, 7, and 10 illustrate environmental subject matter and form no part of the claimed design.
